ABSTRACT: A theft prevention alarm system for use with an electrical appliance which includes a transmitter located within the appliance and which continuously generates an electrical signal of a predetermined frequency over the alternating current power supply lines. A receiver is connected to the alternating current power supply and operates an alarm system when the electrical signal having the predetermined frequency can no longer be detected.

APPLIANCE THEFT PREVENTION ALARM SYSTEM

The general object of this invention is to provide an alarm system to protect electrical appliances from theft. Another object is to provide a system which is sufficiently sophisticated to foil even the most clever thief and yet is sufficiently simple to install that it can be installed and used by the average person in his home. Another object is to provide a system which can be built into an appliance by the manufacturer and marketed with the detection and alarm circuit described herein to provide a built-in theft protection system.

The system described herein differs from and is an improvement over the prior art (c.f. J. Schulein, U.S. Pat. No. 3,411,150) in the following respects:

1. Since the transmitter described herein is situated within the appliance to be protected, the appliance can be plugged into any electrical outlet. This is clearly more desirable than a system such as that of Schulein (in which a transmitter is connected to a special wall outlet) because such a system protects only the appliance plugged into the special wall outlet. The system described herein thus allows the appliances to be protected to be relocated without the necessity of reinstalling the transmitter.

2. The installation of the transmitter within the cabinet of an appliance is sufficiently simple that it can be performed by the average person with no special knowledge of electronics. This system can therefore be made available to the general public, whereas other systems, requiring modifications to household wiring, must be installed by experts.

3. Since the transmitter is out of sight within the cabinet of the appliance, there is no unsightly and revealing evidence near the appliance indicating that it is protected.

4. Since the receiver described herein is designed to work with batteries if the user so desired, the alarm system will function even if the thief attempts to foil the alarm by shorting out the household power circuit.

The system consists of two basic units, transmitter and receiver. The transmitter unit is placed within the cabinet of an electrical appliance and draws its power from the power cord that serves the appliance. The device transmits a low-level electrical signal with a frequency in the range of 20 to 400 kilocycles along the power cord which feeds the device. This signal is not transmitted through the air, and it is blocked by transformers. Therefore, its range is limited to the approximately six houses surrounding the stepdown transformer on the utility pole. The unit is transistorized and operates continuously as long as the appliance to which it is attached is plugged into a wall outlet.

The receiving unit is plugged into a wall outlet. It detects the signal from the transmitter with a tuned circuit, amplifies it, and uses the amplified signal to operate a relay. While the receiver is receiving a signal from the transmitter, the relay is "open." If the receiver ceases to detect a signal from the transmitter, the relay "closes" immediately. The relay, when closed, causes a standard burglar alarm bell to sound. A switch is provided on the unit which allows the user to select either of two operational modes:

1. Auto reset: The alarm will cease to sound if the transmitter is reactivated (i.e., by plugging the appliance to which it is attached back in).
2. Manual reset: The alarm cannot be stopped, once started, except by setting the mode switch (15) on the receiver to "auto."

The transmitters and receivers would be produced in pairs, each pair consisting of one transmitter and one receiver. Each pair might be tuned to operate at a slightly different frequency within the specified frequency range. This is to insure that the transmitter of one pair would not function with the receiver of another pair. (If it were not for this feature, it would be possible for a thief to buy a transmitter and exchange it for the one attached to the object of the theft, thereby foiling the alarm system.)

Two accessories would be used in conjunction with the transmitter. The television power plug accessory provides

power to the transmitter enclosed in the television cabinet from the power socket on the back of the television chassis. All televisions are provided with a safety interlock which disconnects the power to the set when the back is removed. This accessory is plugged into the back of the chassis, and the cabinet back is plugged into it. The accessory delivers power to the transmitter. If the back of the television is removed, the power to the transmitter is automatically cut off.

10 The appliance power patch cord accessory is for use with any electrical appliance. It is a power cord terminated at one end by a female jack connecting to the transmitter, and at the other end by two small alligator clips. The transmitter is placed in the cabinet of the appliance, and it is attached to the power source by means of the alligator clips on the patch cord.

15 The transmitter (FIG. 2) consists of a power supply 1-3 which drives an oscillator circuit 4-8, and a capacitive coupling circuit 9-10 to couple the RF signal back into the AC power lines. Power is supplied to the transmitter through the accessory plug 0.

20 The transformer 1 steps down the voltage from the AC power line and isolates the circuit from the AC line. The reduced voltage is rectified to DC by the full-wave rectifier 2, and the AC ripple is partially filtered out by 3.

25 Initially, an electron current flows through the transformer windings 6 and through the collector of the transistor 4 to ground. The transistor base bias is applied by means of a resistor 5. The current in 6 induces an EMF in 7, resulting in a reduction of the base current of the transistor. The reduced

30 current causes the collector current to drop, reducing the current through 6. The decrease in the current through 6 induces an EMF of opposite polarity in 7, thereby increasing the base current. The increased base current causes an increase in the current through the collector and 6. This process then repeats itself as long as the power is supplied, so that an oscillating current is set up in 6. The frequency of the oscillations is determined by the tuned circuit 8.

35 The oscillating current in 6 induces an oscillating EMF in the secondary windings 9 of the oscillator transformer. This oscillating signal is coupled through the coupling capacitors 1 back into the AC power line.

40 The receiver FIG. 1 consists of a power supply 1-3, a detector circuit 4-7, and a two-transistor amplifier circuit 8-12 which operates a relay 13. Power is supplied to the receiver directly from the AC line by means of the standard AC line plug 0.

45 The transformer 1 steps down the voltage from the AC power line and isolates the circuit from the AC line. The reduced voltage is rectified to DC by the full-wave rectifier 2 and the AC ripple is partially filtered out by 3. The high-frequency signal from the transmitter is capacitively coupled to the primary of the RF transformer 4. The tuned circuit 5 is adjusted by varying the capacitor to resonate at the frequency of the transmitter. The oscillating current induced in the resonant circuit 5 is rectified by the diode 6, and the ripple is filtered out by 7.

50 The weak rectified signal from the detector circuit is applied to the base of the transistor 8, which is biased by means of resistors 9-10. The transistor 8 amplifies the weak detector current, and the amplified current through the emitter-collector circuit of 8 is applied to the base of 12, which further amplifies the current. The current from the two-transistor amplifier actuates a relay 13 which breaks the circuit leading to the alarm. If the signal from the transmitter should cease, the current in the relay would be greatly reduced, so that relay would close and complete the alarm circuit, thereby causing the alarm to sound.

55 The latching relay 14 is used to cause the alarm to continue to sound even if the transmitter is reactivated. To use the latching relay, the mode selector switch 15 is closed manually. Then the alarm, once started, will continue to sound until 15 is opened or the power to the receiver is disconnected. If switch 15 is open the alarm will sound when the transmitter signal ceases, but the alarm will stop if the transmitter is activated.

again. 16 is where receiver attaches to bell transformer or to batteries, and 17 is where receiver attached to alarm bell or buzzer.

It is desired to secure by Letters Patent:

1. A theft prevention alarm system for use with an electrical appliance comprising:

a transmitter including a power plug for connection within the case of an electrical appliance to the alternating current power cord of the electrical appliance, 10
said transmitter including an oscillator operable by electrical power supplied through the power cord of the appliance to generate an electrical signal of a predetermined frequency, 15
a transformer connected between said oscillator and the power cord to couple said electrical signal into the alternating current power supply,

a receiver including an isolation transformer for connection into the alternating current power supply remote from said appliance, 5
a rectifier connected to said isolation transformer for providing DC bias voltage for said receiver, 10
a tuned circuit tuned to said predetermined frequency, 15
a second transformer for coupling said electrical signal having the predetermined frequency to said tuned circuit, 20
amplifier means for amplifying the output from said tuned circuit, 25
switch means operable by the output from said tuned circuit, and 30
an alarm system operable in response to said switch means to provide an alarm indication when said receiver ceases to detect said predetermined frequency electrical signal.
